THERAPEUTIC MACHINE

Frank L. Carson, Hollywood, Calif.

Application June 4, 1958, Serial No. 739,856

2 Claims. (Cl. 128—25)

This invention relates to a therapeutic machine of simple construction for exercising and massaging various parts of the body to stimulate circulation and to restore or improve the muscular condition of the parts being treated.

Another object of the invention is to provide a therapeutic machine capable of effectively functioning as a weight reducer and for slenderizing the parts of the body being treated.

Other objects and advantages of the invention will hereinafter become more fully apparent from the following description of the drawings, illustrating a presently preferred embodiment thereof, and wherein:

Figure 1 is a side elevational view, partly in section and partly broken away, of the therapeutic machine;

Figure 2 is an enlarged longitudinal sectional view, partly in elevation, of a portion of the machine, taken substantially along a plane as indicated by the line 2—2 of Figure 3;

Figure 3 is a horizontal sectional view, taken substantially along a plane as indicated by the line 3—3 of Figure 2;

Figure 4 is a cross sectional view of a part of the machine, taken substantially along a plane as indicated by the line 4—4 of Figure 2;

Figure 5 is an enlarged fragmentary vertical sectional view of a part of the machine;

Figure 6 is a view similar to Figure 5 illustrating another part of the machine in detail;

Figure 7 is a diagrammatic view illustrating the electric circuit of the machine, and

Figure 8 is a fragmentary side elevational view of a part of the machine.

Referring more specifically to the drawings, the therapeutic machine in its entirety is designated generally 10 and includes an elongated housing, designated generally 11, composed of a substantially flat bottom 12, side walls 13, end walls 14 and 15 and a top wall or cover 16. The side walls and end walls have projections extending inwardly from the corners thereof at the top of said walls, as seen at 17, and which have threaded bores to receive screw fastenings 18 for securing the top wall or cover 16 in its applied position, as illustrated in the drawings. Laterally spaced caster wheels 19 are secured to and depend from the bottom 12, adjacent the front wall 14, and short legs 20 are secured to and depend from the bottom 12 adjacent the other rear end wall 15, for supporting the casing or housing 11 in a slightly elevated position relative to a floor or other supporting surface 21. The front wall 14, adjacent the corners thereof and on its outer side, is provided with bumpers 22 which may be formed of any suitable cushioning material, such as rubber, for supporting the housing 11 in an upright position for storage. The rear wall 15 on its outer side and adjacent its top is provided with a handle 23, by means of which the housing can be manipulated on the caster wheels 19 by slightly elevating the legs 20, for moving

2

the housing to a desired location for use or to a position to be stored in an upright position.

Two hollow bearing posts 24 and 25 are secured to the upper side of the bottom 12 and are disposed in upright positions within the housing 11, in spaced apart relation to one another and to the side and end walls of the housing, as seen in Figures 2 and 4. The bearing post 24 is located between the front wall 14 and the bearing post 25 and has a fixed mounting bracket 26 to which the base 10 of an electric motor 27 is secured by fastenings 28, for supporting the motor on said bearing post 24, between said bearing post and the front wall 14. A motor drive shaft 29 projects upwardly therefrom and has a belt pulley 30 fixed thereto.

As seen in Figure 5, the upper end of the bearing post 24 is internally recessed, as seen at 31, to accommodate an antifriction ball bearing unit 32 in which is journaled a shaft 33. The upper end of the bearing post 25 has a similar internal recess 34 to accommodate a second antifriction bearing 35 in which is journaled a shaft 36.

A belt pulley 37, of substantially larger diameter than the belt pulley 30, is fixed to the upper end of the shaft 33 and is supported thereby above and adjacent the upper end of the bearing post 24. A belt pulley 38, which is 25 of substantially larger diameter than the belt pulley 37, is fixed to and supported by the upper end of the shaft 36 and is disposed immediately above the upper end of the bearing post 25. The upper end of the bearing post 25 terminates below the upper end of the bearing post 24 and the belt pulley 38 is disposed below the level of the belt pulley 37 and partially underlies said belt pulley 37, as seen in Figure 2. The belt pulley 38 is disposed coplanar with the belt pulley 30 and is connected thereto by an endless belt 39. A hub 40 of the belt pulley 38 extends upwardly and is provided with an annular groove to form a small belt pulley 41 which is thus integrally connected to the belt pulley 38, and which belt pulley 41 is disposed in the same plane as the belt pulley 37 and is connected to said belt pulley 37 by an endless belt 42.

The upper side of the belt pulley 37 has a raised radially extending rib 43 the upper surface of which slopes downwardly toward the periphery of said belt pulley, as seen in Figure 5. The rib 43 is provided with an upwardly opening socket 44 which is likewise disposed at an angle upwardly and outwardly relative to the plane of the belt pulley 37, and in which is mounted an antifriction ball bearing unit 45 having an inwardly tapered bore 46 at the center thereof. The hub 40 of the belt pulley 38 has an enlarged upper end disposed above the small belt pulley 41 and forming a head 47 which is provided with an upwardly opening socket 48. The socket 48 is eccentrically disposed relative to the axis of the hub 40 and is inclined upwardly and outwardly, relative to the center of the hub. The socket 48 also contains an antifriction ball bearing unit 49 having a tapered bore 50, which tapers downwardly and inwardly thereof. The uppermost portion of the hub of the pulley 37 and the rib 43 extends slightly into an opening 51 in the top wall 16, and the upper end of the head 47 extends slightly into a smaller opening 52 of said top wall 16, as seen in Figure 2. However, said portions 37, 43 and 47 terminate below the level of the upper surface of the top wall 16.

The intermediate portion of a crossarm 53 is rigidly secured to the upper end of a rod 54. The rod 54 is provided with an enlargement 55 at its lower end which tapers outwardly or downwardly and which is of a proper size and shape to fit snugly in the bore 46. Plates 56 are secured to the ends of the crossarm 53 in laterally spaced relation to the rod 54 and are preferably disposed coplanar. Flexible shoe or sandal-like members 57 are immovably secured to forward sides of the plates 56 and have strap and buckle means 58 for securing said

members 57 on the two feet of a person using the therapeutic machine.

A disc shaped pad 59 has a tapered stud 60 secured to and projecting from the central portion of its underside, as seen in Figure 6, and which is of a proper size and shape to fit snugly in the bore 50 of the antifriction bearing 49.

The therapeutic machine 10 also includes two body supporting members 61 and 62, each of which includes an elongated top portion or platform 63. Laterally spaced supporting legs 64 are fixed to and depend from the corners of one end of each platform 63, and studs 65 are fixed in and depend from the corners of the other end of the platform. The body supporting member 61 differs from the body supporting member 62 in that it additionally has apertured brackets 66 fixed to and extending beyond the first mentioned end thereof and which project from the undersides of said first mentioned corners. The top wall 16, adjacent the rear end wall 15, is provided with transversely spaced openings 67 to receive the studs 65 of the supporting member 61, so that one end of the supporting member 61 is supported by the housing 11 while the opposite end thereof is supported by the legs 64. The studs 65 of the supporting member 62 engage in the apertures of the projections 66 for supporting one end of said member 62 while the other outer end thereof is supported by its legs 64. The body supporting members 61 and 62 are thus positioned in end-to-end relation extending from the rear end of the housing 11, as seen in Figure 1. The body supporting member 62 may be alternately positioned, as illustrated in dotted lines in Figure 1, with the inner portion thereof overlying the forward part of the housing 11 and with the studs 65 of the body supporting member 62 engaging transversely spaced openings 67' of the top wall 16, so that the member 62 projects from the forward end 14 of the housing 11.

An electric cord 68 extends from the motor 27 through an opening 69 in the rear wall 15, as seen in Figure 2, and is adapted to be connected to any conventional domestic electrical outlet. An electric switch 70 is interposed in the electric cord 68 beyond the rear end 15 of the housing in any position so that it can be operated by the user while lying upon the body supporting members 61 and 62. The switch 70 is preferably of the rheostat type, as illustrated in Figure 7 for varying the speed of operation of the motor 27.

Assuming that the body supporting members 61 and 62 are positioned in end-to-end relation extending from the rear end of the housing 11, as illustrated in full lines in Figure 1, and that the user of the machine 10 is lying thereon and with his or her feet secured in the sandal members 57, the switch 70 is actuated for closing a circuit to the motor 27. The drive pulley 30 of the motor drives the large pulley 38 at a considerably reduced speed relative to the speed of rotation of said pulley 30 and the pulley 41 in turn drives the pulley 37 at a substantially reduced speed relative to the r.p.m. of the pulleys 38 and 41, so that the belt and pulley drives form a reduction drive from the pulley 30 to the pulley 37. Thus pulley 37 and its bearing 45 is revolved at a very slow speed relative to the r.p.m. of the drive pulley 30. As seen in Figure 2, the plates 56 and sandal members 57 are disposed at approximately the same level and are inclined downwardly and forwardly when the rod 54 is in its rearmost position of Figure 2. As the shaft 33 and pulley 37 make a quarter turn clockwise, as seen in Figure 3, for example, the rod 54 will assume a position extending laterally upward at an incline away from the axis of the shaft 33 and the cross-arm 53 will be inclined downwardly and outwardly, so that the sandal members will be disposed at different levels. Said sandal members 57 and the plates 56 will then be disposed substantially in vertical planes. Another 90° turning of the pulley 37 will position the bear-

ing 45 opposite to its position of Figure 2, in which position the rod 54 will be inclined upwardly and to the left of Figure 2, the crossarm will have been returned to the horizontal position and the plates 56 and sandal members 57 will be inclined in the opposite direction or upwardly and to the left, corresponding to the inclination of the rod 54. A further 90° turning of the pulley 37 will position the bearing 45 to the right of its position of Figure 4 so that the rod 54 will then be inclined upwardly and to the right, the crossarm 53 will be inclined downwardly and to the right and the plates 56 and sandal members 57 will again be in substantially upright positions. A further 90° turning of the pulley 37 in the same direction will return the parts to their positions of Figure 2. It will be readily apparent that this movement of the sandal members 57 in the circular path combined with a rocking movement thereof will exercise and massage the legs and ankles. It will be apparent that as the rod 54 and cross arm 53 move in a circular path that the inner race of the bearing 45 will turn in the outer race thereof so that the rod 54 will not rotate about its axis and there will be no rotation of the crossarm 53, plates 56 or sandal members 57, which sandal members and plates 56 will always retain positions to the right of the crossarm 53, as seen in Figure 2.

The pad 59 moves in a circular path having a small radius, as clearly indicated in Figure 6, and said pad is maintained canted at all times and is capable of rotating about the axis of the stem 60 or may be held against rotation about said axis. The pad 59 may be utilized simultaneously with the parts 57 to engage and massage parts of the legs as the legs are extended by movement of the sandal members in a circular path for effecting spot reducing by vibratory slapping engagement of the upper surface of the pad with the legs. In addition, while the legs are out of contact with the pad, said pad will commence to rotate about the axis of its stem 60 so that when the flexing legs again contact the pad an additional twisting pressure will be exerted against the flesh. If desired, the pad 59 may be removed while the sandal members 57 are being utilized, and the rod 54 and the parts supported thereby may be removed while the pad 59 is in use. When the rod 54 and associated parts are removed and the pad 59 alone is employed, the body supporting member 62 may be mounted in its dotted line position of Figure 2 so that the pad may be employed for spot reducing of different parts of the torso of the body of the patient and while the patient is lying on both body supporting members 61 and 62 with a part of the torso bridging the gap between said body supporting members and which bridging portion is disposed to be engaged by the pad 59.

Various modifications and changes are contemplated and may be resorted to, without departing from the function or scope of the invention as hereinafter defined by the appended claims.

I claim as my invention:

1. A therapeutic machine comprising an elongated housing having a top wall provided with longitudinally spaced openings, two upright journals secured within said housing beneath said openings, shafts rotatably supported in said journals and projecting from the upper ends thereof, a power source fixedly supported within said housing, a belt and pulley drive connecting both of said shafts to the power source for revolving the shafts simultaneously at different speeds, bearing supports fixed to the upper ends of said shafts and disposed for rotation within the housing, a bearing mounted in each bearing support and eccentrically disposed relative to the axis of the shaft thereof, said bearings each including an upwardly opening socket, the axes of said sockets being inclined upwardly and outwardly relative to the axes of the shafts, a rod having a lower end detachably mounted in one of said sockets, said rod extending upwardly through one of said openings, a crossarm fixed to said rod and disposed above

the housing, foot attaching members rigidly connected to the ends of said crossarm on opposite sides of and spaced from said rod, a pad disposed above the other opening of the housing and having a depending stud extending downwardly through said last mentioned opening and detachably mounted in the other bearing socket for supporting the pad at an incline relative to the top wall of the housing, said foot attaching members and the pad being simultaneously rotated with the bearing supports around the shafts individual thereto and being rotatable with the bearing sockets thereof relative to the bearing supports, when the shafts are driven by the power source.

2. A therapeutic machine as in claim 1, body supporting members, and means interconnecting said body supporting members to one another and to an end of the 15

housing for mounting the body supporting members in end-to-end relation relative to one another and relative to the housing, and means for selectively mounting an outer one of said body supporting members on an opposite end of said housing and with said pad disposed between adjacent ends of said body supporting members.
